UNITED STATES PATENT OFFICE.

WILLIAM M. WILLIAMS, OF GRIDLEY, CALIFORNIA, ASSIGNOR OF ONE-HALF TO J. L. MINTS, OF GRIDLEY, CALIFORNIA.

ORE-JIGGER.

No. 923,917.

Specification of Letters Patent.

Patented June 8, 1909.

Application filed December 8, 1908. Serial No. 466,516.

To all whom it may concern:

Be it known that I, WILLIAM M. WILLIAMS, a citizen of the United States, residing at Gridley, in the county of Butte and State 5 of California, have invented a new and useful Ore-Jigger, of which the following is a specification.

This invention relates to ore jiggers of the reciprocating screen type, and has for its 10 object to provide an improved screen structure, and also to augment the upward flow of the water through the screen, in order to effect a better and more rapid separation.

With these objects in view, the invention 15 consists in a novel construction and arrangement of parts to be hereinafter described and claimed, reference being had to the drawing hereto annexed in which—

Figure 1 is an elevation of the apparatus, 20 partly in section. Fig. 2 is an enlarged sectional detail of the screen bottom of the jig-box. Fig. 3 is a transverse section on the line 3—3 of Fig. 1.

Referring more particularly to the drawing, 5 denotes the tank in which the jig-box 6 works. The tank is filled with water, and the jig-box is reciprocated therein as usual. The resistance of the water, as the box descends, lifts up the ore, and the particles 30 assort themselves as they settle back, the denser particles being arranged in strata under the less dense.

The jig-box is suspended in the tank from one end of the lever 7 which is fulcrumed 35 at 8 on standards 9 rising from the tank. To each end of the jig-box is pivoted a link 10 which is connected to a hook 11 carried by and depending from the lever. On each end of the jig-box is also mounted a bracket 40 12 having a segmental slot 13 in which works a pin 14 carried by and projecting from the links, whereby the movement of the box is regulated.

In the bottom 15 of the jig-box, are outwardly tapering perforations 16, and on said bottom, on the inside of the box, is mounted a double screen 17 bedded with a layer 18 of granular material, on top of which is arranged a grating comprising rods 19 which 50 extend lengthwise of the box, and are secured at their ends to the end walls thereof in any suitable manner. The granular material is preferably chilled shot. This structure forms a screen which is strong and

durable, and which effects a thorough separation. 55

In the tank, below the jig-box, is mounted a trough 20 which is properly dimensioned to receive the concentrates dropping through the screen bottom of the jig-box. The jig-box works adjacent to the forward end of the tank, and the trough extends to that end, but is spaced from the opposite end of the tank. The bottom of the trough slopes downwardly in the direction of the last 60 mentioned end of the tank, and the trough is also open at that end. To the bottom of the trough, at its open end, is hinged at 21, to swing in a vertical plane, a gutter 22 which works between said end of the trough 65 and the adjacent end wall of the tank. The gutter is connected by an arm 23 to a link 24 carried by a stem 25 secured to and depending from the lever 7, the stem being connected to the lever on that side of its 70 fulcrum opposite to that from which the jig box is hung. By reason of this connection between the gutter and the lever, it will be seen that when said lever is swung to reciprocate the jig box, the gutter will swing 75 upwardly on its hinge every time the jig box descends, whereby a current of water is forced into the space between the trough and the bottom of the jig-box, and upwardly through the screen, the action being 80 similar to that in the type of jiggers having a stationary screen, through which the water is caused to pulsate by a plunger. By thus combining the actions of the two types of apparatus, a better and more rapid separation 85 is effected. The gutter 22 also serves as a valve closing the space between the trough and the tank walls, and timed to close at the same time the jig box descends, 90 whereby the forcing out of the liquid by the box is prevented; then when the jig box ascends, this valve trough drops, and discharges its contents below the trough, and permits a moderate discharge of water and material through the pipe 26 to the sluice 27. 95 100

The concentrates passing through the screen, drop on the trough 20, and work down the same into the gutter 22, from which they are discharged over the ends there onto the bottom of the tank. The sand and water is discharged through a pipe 26 leading to a sluice 27 which is located outside the tank, and which is V-shaped in 105

cross-section as clearly shown in Fig. 3 of the drawings, and bedded with shot or any other suitable material 28 for catching particles heavier than water, the object being to 5 save the finer particles of ore. By making the perforations 15 tapering the concentrates passing through the screen are more evenly distributed.

What is claimed is:

- 10 1. The combination with a tank, a jig-box working therein, and means for operating the jig-box, a trough in the tank below the jig-box, said trough being open at one end, and the bottom of the trough sloping in the 15 direction of said open end, a gutter hinged to the open end of the trough and fitting between said end and the adjacent wall of the

tank, and a connection between the gutter and the aforesaid jig-box operating-means.

2. The combination with a tank, a jig-box 20 working therein, and means for operating the jig-box, of a trough in the tank below the jig-box, a gutter hinged at one of its longitudinal edges to the discharge end of the trough and fitting between said edge 25 and the adjacent wall of the tank, and means for rocking the gutter.

In testimony that I claim the foregoing as my own, I have hereto affixed my signature in the presence of two witnesses.

WILLIAM M. WILLIAMS.
